United States Patent Office.

SEWELL E. JEWETT, OF HAVERHILL, MASSACHUSETTS, ASSIGNOR TO HIMSELF AND
OSGOOD G. BOYNTON, OF SAME PLACE.

Letters Patent No. 89,150, dated April 20, 1869.

IMPROVEMENT IN SHUTTER-WORKER.

The Schedule referred to in these Letters Patent and making part of the same.

To all persons to whom these presents may come:

Be it known that I, SEWELL E. JEWETT, of Haverhill, in the county of Essex, and State of Massachusetts, have invented a new and useful Mechanism for Operating and Fastening Window-Blinds or Shutters; and I do hereby declare the same to be fully described in the following specification, and represented in the accompanying drawings, of which—

Figure 1 is a front elevation, and

Figure 2, a side view of a blind and window-frame with my invention applied thereto.

Figure 3 is a vertical, and

Figure 4, a horizontal section, taken through the operative lever and parts connected therewith.

Figure 5 is a transverse section of the gravitating blind-catch, the window-frame, and the lower portion of the blind.

On February 11, 1868, Letters Patent of the United States of America, numbered 74,227, were granted to me for an improvement in mechanism for operating window-blinds or shutters.

My present invention involves the principle of that improvement, but includes an addition, by which the device, or bar and cam used in effecting the opening and closing of the blind or shutter, may also be employed to raise it, in order to unlatch it, the latching of the blind or shutter being effected by a self-operating, or gravitating catch.

In the drawings, the blind is shown at A, and the window-frame at B, they being hinged together, as exhibited at C D.

A lever, or slide-bar, E, (provided with a knob, a, at its inner end, and a slotted head, b, at its outer extremity,) extends through one of the upright bars of the window-frame, or a tapering passage, e, made therein.

At the opposite ends of the passage, two escutcheon-plates, d e, are affixed to the frame.

The lever, or bar E goes through slots f g, made in these plates, the rearmost slot being considerably longer than the foremost one.

Against the inner side of the plate d, and so as to serve as a cover to its slot, is a plate, h, through which the bar E goes. The said plate h moves up vertically with, and will be so moved by the bar E, when used as a lever, and serves as a "wind cut-off," or as a means of preventing a draught, or current of air from entering the room through the slots f and g.

The slotted head b of the rod E, having the form, and being slotted in manner as represented in the drawings, receives a vertical pin, i, which extends through it, and two arms, or brackets, k k, projected from the blind, in manner as shown in figs. 1 and 2.

The bar E rests on the lower edge of the slot of the foremost escutcheon-plate, which serves as a fulcrum to enable the bar, when moved downward by the hand

of a person, applied to its knob, to force the blind upward, so as to unlatch it, whether the blind be either entirely opened or closed.

Instead of using a common spring duplex-catch, such as is commonly employed to hold a blind, either closed or opened, I make use of a rotary and gravitating catch.

It consists of a socketed cylindrical weight, F, and a box, or bearing, G, for supporting it.

The gravitating catch F is constructed with a flange, or head, k, at its upper end, which is to support the catch on the top of the bearing, G.

There is a cylindrical chamber, or recess, l, formed in the catch, so as to open out of its inferior end, and the lower part of the catch, around this recess, is bevelled, chamfered, or tapered, as shown at m.

The bearing, G, consists simply of a plate, n, and a cylindrical tube, o, projecting from it, and opening through such plate. This bearing is applied and fastened to the lower part of the blind, in order that the catch may operate with either of two studs or catches, p q, one of which should project from the window-sill s, and the other from the side of the building to which the window-frame may belong, the whole being so as to enable the blind to fasten itself upon either of the catches p q.

The rotary gravitating catch is better than a spring-catch, because, with the latter, the blind would have to be raised higher to effect its disengagement, and furthermore, with the gravitating catch, made as described, so as to be capable of being revolved in its bearing or socket, it will revolve more or less, from time to time, when in use, so as not to become worn in one place, the wear being distributed over the entire circle of the bevel or chamfer of the catch.

Thus, the rotary gravitating catch, made as described, will be more durable, and less liable to get out of order, and will operate, in many respects, better than a common catch, made with two cams or inclines only, standing in opposite directions from the recess or notch.

In figs. 2 and 3, t denotes a turn-button, or stop, which is arranged underneath the lever E, and turns on a screw, u, inserted in the window-frame.

By turning the stop t upward, so that the lever E may rest on the free end of the stop, when such lever is in position as shown in fig. 3, the stop will serve as a means of supporting the lever, so as to prevent the blind from being raised by a person on the outside of the house, and for the purpose of unlatching the blind.

By means of the lever E, I not only raise the blind or shutter, so as to disengage or unlock it, but, by forcing the lever forward, until the blind is half open, and next pulling it back, I can effect either the entire opening or closing of the blind.

I am aware of the patent of Cheney Reed, dated August 1, 1848, which is for an improvement in mech-

anism for operating blinds, and I make no claim to any mechanism, or combination of parts described therein.

My gravitating blind-catch has its part F made so that it can revolve horizontally, as well as play or rise and fall vertically, and such part has a shoulder, to support it in its socket-piece G, which is fixed to the blind, all of which differs from any catch shown in the said patent.

Furthermore, the lever E does not turn on its axis, and has no reversible inclined plane applied to it, like that shown in such patent of Reed, as applied to the end of the shaft which goes through the window-frame.

My lever simply slides lengthwise, in order to effect the opening or closing of the blind; and besides, the lever has the escutcheon-plate e as a fulcrum, and is applied to the window-frame in or by an opening, c, which will admit of the lever E being moved up and down as a lever, the lower edge of the hole in the plate e being the fulcrum.

The slotted head of the lever operates, with the pin i, to effect the horizontal movement of the blind when the lever E is moved longitudinally.

I therefore, herein, make no claim to the bar E, its

slotted head b, and the pin i, as arranged and applied to the blind and the window-frame, in manner and simply for the purpose as set forth in my said patent; but, in combination therewith,

I claim the application of the bar E to the window-frame, so that while capable of being moved longitudinally, so as to effect the opening or closing of the blind, such bar may be moved downward on a fulcrum, and used as a lever, to effect the elevation of the blind or shutter, for the purpose specified, preparatory to its being opened or closed by means of such bar, slotted head, and pin, as set forth.

I also claim the combination and arrangement of the wind-guard plate h with the escutcheon-plate d, the lever E, and its passage e, when such lever is applied to the blind by means as explained.

I claim the combination of the movable stop t, or its equivalent, with the cammed lever E, the pin i, and the latching-mechanism of the blind, the purpose of such stop being as explained.

SEWELL E. JEWETT.
